UNITED STATES PATENT OFFICE.

ARMAND V. POURROY, OF OAKLAND, CALIFORNIA.

SHEET-METAL PISTON.

Application filed April 6, 1922. Serial No. 549,985.

To all whom it may concern:

Be it known that I, ARMAND V. POURROY, a citizen of the United States, residing at 2914 East 19th Street, in the city of Oakland, county of Alameda, and State of California, have invented a new and useful Sheet-Metal Piston, of which the following is a specification.

My invention relates in general to pistons, and more particularly to a light-weight, removable-shell piston for the internal-combustion engine of the ordinary motor vehicle in common use.

Heretofore the usual types of pistons known to me, have been made of cast iron, cast aluminum, or other cast material, cast in a single piece. This necessitated machining the casting very carefully to insure the proper size, smoothness and polishability, and also to insure the proper functioning of those parts integral with the piston, particularly the wrist pin. Difficulty has been experienced with pistons made of cast iron, due to their excessive weight and tendency to wear unevenly and become out-of-round, necessitating replacing the piston with a new one. Difficulty has also been experienced with pistons made of cast aluminum and other alloys, due to their lack of mechanical strength, their tendency to excessive expansion, their inability to take a polished surface, and to their lack of resistance to wear and tendency to become out-of-round, necessitating replacing the piston with a new one. Difficulty has also been experienced in the present type of piston, due to the wrist pin creeping from its normal position and "scoring" the cylinder walls.

Therefore, the principal objects of my invention, are: to overcome the above difficulties by the provision of a built-up piston, comprising an external shell of sheet metal possessing wearing qualities and an interior cast aluminum or other alloy frame. In my piston is gained, lightness combined with resistance to wear, cheapness of manufacture, means for securing the wrist pin in a full floating position in conjunction with

the elimination of "scoring" possibilities, and mechanical superiority with special reference to replacing the shell, the part subjected to excessive wear with a new one when the old one is worn, instead of discarding the entire piston. The invention possesses other objects and features of advantage, some of which, with the foregoing, will be set forth in the following description of the preferred form of my invention taken in connection with the drawing, which constitutes a part of my invention, and in which:

Figure 1 is a sectional elevation of my piston, the wrist pin and bolt being shown in full.

Fig. 2 is a similar elevation, taken on the line A—A of Fig. 1.

Fig. 3 is a plan view of Fig. 1 with the shell and bolt removed.

Fig. 4 is a cross sectional view of Fig. 2, taken on the line B—B with the shell removed, and looking in the direction of the arrows.

Fig. 5 is an elevation similar to Fig. 1, and is a part of a modified form of the piston and shows the frame secured to the shell by more than one bolt.

Briefly expressed, my invention is a piston in the form of a built-up structure, and comprises an interior frame of cast aluminum or other light-weight alloy, having the customary bosses for the support of the wrist pin, a removable exterior shell of sheet metal formed from a single sheet with recesses thereon for the reception of piston rings, and means for securing the shell to the frame, whereby the wrist pin is supported in a full-floating position and without lateral movement.

A detailed description of the illustrated embodiment of my invention follows:

Referring to the drawings, the shell 1 is preferably formed of sheet steel and has an opening at one end and is closed at the other end, the closed end may be dished as illustrated and the open end provided with an annular flange 2 to gain structural strength. The shell has ring grooves 3 formed thereon

near the closed end for the reception of piston rings, and a wider groove 4 near the open end, forming a walled flange 5 for the purpose of centering and snugly retaining 5 the ring-base 6 of the frame in position.

The frame is preferably made of cast aluminum or other light-weight alloy, and is adapted to slip into position in the shell and be securely bolted thereto by bolt 7 and 10 nut 8, the nut being locked in position by cotter pin 9 suitably disposed in one of the grooves 10 in the nut.

The shell and the frame are both so proportioned that when bolted together, the 15 boss 11 on the frame top fits against the closed end of shell, and the ring-base 6 of the frame is contiguous to the annular flange 5 of the shell.

The frame is basket-like in structure and 20 has a disc-like or umbrella top 12 surmounted by boss 11, and a tubular or ring-base 6 provided with a pair of bosses 13 diametrically opposed, the top and base being connected by arms 14 which terminate in the 25 ring bosses. The diameter of the top 12 is slightly less than that of the ring-base 6, as it is preferably desired that the only circumferential machine finish of the frame shall be that of the ring-base.

30 The ring-base may have one or more slits 15 cut through its wall to relieve the excess stresses of the piston due to heat expansion in service.

The umbrella top also functions as a protector for the top or closed end of the shell, by preventing the splashing of oil against the explosion wall of the piston.

Effective heat radiation is also a feature of advantage with my type of piston, as the 40 entire inner surface of the piston shell is substantially in contact with the air, thus increasing the efficiency of the engine to a marked degree.

From the drawing, it is evident that the 45 wrist pin 16 would necessarily have to be in its proper position before the assembling of the shell with the frame, and it is also evident that the wrist pin cannot become engaged with, and "score" the walls of the cylinder within which the piston might be moving, as the wrist pin is prevented from lateral movement by the annular flange 5 of the shell; the wrist pin does not have to be secured in place by any of the methods usually employed, and is, in fact, full-floating in action.

In the modification of my invention shown in Fig. 5, the head of the shell is flat instead of bumped as in Fig. 1, and the frame is secured to it by a plurality of bolts. In some cases, I may prefer to use this type of construction.

While I have shown and described my invention in detail, I do not wish to be limited 65 to the invention precisely as illustrated, but

wish to include all variations of it that come within the spirit and scope of the invention as claimed.

What I claim as new and desire to secure by Letters Patent is:

1. In a piston, a single-piece shell provided with narrow ring grooves near its top, and a wide ring groove below said narrow ring grooves, the internal peripheral surface of said wide groove forming a bearing- 70 wall.

2. In a piston, a sheet metal shell formed with narrow ring grooves near its top, and a wide ring groove toward its bottom, the latter groove provided for reinforcement and 80 bearing means.

3. In a piston, a cast frame of basket-like construction provided with a disc-like top and a ring-base, the central area of said top and the outside circumferential area of said 85 base being contact surfaces, for engagement with the shell member of the piston, and said ring-base provided with a slit for expansion relief.

4. In a piston, a cast frame having an umbrella top and a ring-base, and having formed therebetween a pair of arms diametrically opposed, each arm terminating in a boss on the ring-base, the said top and said 95 bosses provided with holes for the reception of supporting means, the said arms being the only means connecting said top to said base, thus permitting effective heat radiation from the piston.

5. In a piston, in combination with a sheet- 100 metal shell, a basket-shaped interior frame having a bossed-top and a bossed-ring-base and connecting arm members therebetween, said bossed parts provided with supporting elements.

6. A piston, comprising a cupped, single-piece grooved sheet metal shell and a metallic basket-like frame of basket form adapted to fit within the shell and be removably secured thereto.

7. A piston, comprising a sheet metal external shell and a cast internal frame of basket form having a disc-like top and a ring-base, the said top adapted to engage the shell top and the said base adapted to engage the wall of the shell, and the body of the frame spaced from the shell for effective heat radiation.

8. A piston, comprising a sheet metal external shell and a cast internal frame, the latter having a disc-like top and a ring-base, the said top adapted to engage the shell top and the said base adapted to engage the wall of the shell, the ring of said ring-base being slotted for expansion relief.

9. A piston, comprising a grooved external sheet metal shell, an internal frame and a wrist pin; the latter adapted to be floatably supported in the frame, and said frame provided with means for detachably securing 120

the frame to the shell, the said shell enveloping the wrist pin, thereby preventing lateral movement of the pin, but allowing the full flotation thereof.

5. 10. In combination, a piston, piston rings and a wrist pin; the piston comprising a cupped, single-piece grooved sheet metal wearing shell of continuous surface and a frame of basket form and means for secur-
- ing one to the other, the piston rings adapted for engagement with the shell grooves, and the wrist pin adapted for engagement with the frame, the said wearing shell adapted for replacement on said frame, the shell enveloping the frame and the contained pin, thereby locking the pin in position but allowing the same to float in rotation.

ARMAND V. POURROY.
